UNITED STATES PATENT OFFICE

ROBERT F. RINGLE, OF ZELIENOPLE, PENNSYLVANIA

FLASK-SUPPORTING MEANS FOR TURNOVER DEVICES

Application filed July 2, 1929. Serial No. 375,559.

My invention refers to improvements in molding machines of the general type illustrated in prior patent of Austin and Ringle #1,243,030, of October 16, 1917. It has in view to provide means for making operative engagement between the raising and lowering equalizing table and the flask for accurate engagement therebetween and for lowering the flask from the pattern after molding, and reversal of the flask.

The invention specifically relates to the construction of the connection between the turnover arms and the associated bracket mechanism for supporting the turnover plate, whereby to effect easy movement with continuous support and prevention of shock due to changing relations of the parts and gravitating tendency.

Also, to provide means for securely and effectively combining the turnover arms with such supporting mechanism as to effect easy and convenient separation when desired, with maintenance of relationship during turning and in the suspended position of the turnover plate and the pattern and associated flask prior to adjustment thereto of the equalizing table and removal of the flask downwardly.

The complete molding machine and the present improvement are embodied in an entire operative mechanism including the jarring table on which the flask and its contained sand are vibrated or agitated; turnover mechanism by which the flask and the packed sand surrounding the pattern are elevated away from the jarring table and rotated one-half revolution for location above the lowering mechanism, and such lowering mechanism and equalizing table, and the operative parts thereof forming the subject matter of the present application.

In the drawings illustrating one preferred embodiment of the invention:

Fig. 1 is a general view in elevation, partly in section and partly broken away, showing the several main elements of the installation;

Fig. 2 is a detail view in elevation partly in section showing the outer end portion of the turnover arm and its connection with the turnover plate-supporting bracket;

Fig. 3 is an edge elevation thereof;
Fig. 4 is a sectional detail view on the line IV—IV of Fig. 3;

Fig. 5 is a detail view in side elevation showing the adjusting end for the bearing shoe;

Fig. 6 is a view similar to Fig. 2, showing the position of the parts when the turnover arm is erected.

The motor actuating or power imparting unit for the turnover and flask lowering mechanism is generally indicated at A and is in operative relation to the jarring machine B, both of which are of well known construction, and generally similar to the apparatus shown in the above mentioned patent.

The jarring machine B is provided with the usual table 2 upon which the flask 3 is supported with the intervening pattern supporting turnover plate 4. These elements, as well as the vibrating mechanism for jarring the table, are of well understood construction and operation, and need not be further described.

The turnover plate 4 is provided at each end with laterally extending side arms 5 having outwardly open tapered sockets 6, tapering upwardly when the turnover arms are in laterally extended position for placement of the flask on bumping machine B, as in Figs. 1, 2 and 3.

Each turnover arm 7 is provided with a co-acting tapered wedge or socket block or key 8 conforming to the tapered socket 6 and fitting upwardly thereinto in such position, such block being pivotally connected with the outer end of arm 7 by hinge pin 9.

The controlling rods 10 are provided with connected heads 11 which are pivotally connected at 12 with a stud extending outwardly from the outer end of wedge block 8. Head 11 is also provided with a covering protecting hood 13, completely surrounding the outer terminal end of arm 5 for protection thereof from dust, sand, or other foreign matter.

Head 11 is also provided with a slidably mounted shoe 14 formed with a groove 15 adapted to engage a tongue 16 upon the rear face of head 11. The shoe 14 is further provided with slotted openings 16a to receive

screws or bolts 17 for securing the shoe to the head.

A central adjusting screw 18 having a lock nut is mounted for adjustment inwardly or outwardly of shoe 14, to adjust it to proper bearing position or relation to the outer rounded head 19 of arm 5, when the turnover arms 7 are thrown around to the flask removing position shown in dotted lines in Figs. 1 and 6. Shoe 14 at its inner end is formed with an arcuate surface 20 adapted to receive the rounded head 19 of the arm 5, when the flask is erected as in Fig. 6.

Arms 7 are mounted on rock-shaft 21 extending across in bearings 22 of the main frame of the machine A, and operatively connected by a lever 23 and connecting rod 24 with plunger 25 of cylinder 26. Said cylinder and its parts are generally similar to those of the said patent and operate to throw lever 23 and rock-shaft 21 around through one-quarter revolution, more or less.

Rotation of the turnover plate 4 and flask 3 is effected by restraining or limiting action of controlling rods 10 pivotally mounted at 12 and 27, so that as the turnover arms swing upwardly and over, the position of the flask is reversed above the equalizing table C, as shown in Fig. 1.

In operation, the parts are first positioned as shown in full lines in Fig. 1. In this position the table 2 of the jarring machine B is alternately raised and lowered to jar the sand and the flask 3. During such jarring operation the turnover plate 4 and its arms 5 will be alternately raised and lowered, and tapered sockets 6 will alternately leave and engage co-acting tapered socket blocks 8.

When the jarring operation is completed, fluid such as compressed air is admitted to the cylinder 26 by any suitable control means (not shown), whereby motion is imparted to piston 25 and connecting rod 24, raising the arms 7 by means of lever 23 and rock-shaft 21, to the position shown in dotted lines in Fig. 1. During this rotation controlling rods 10 rotate the turnover plate 4 and its arms 5 about the pivot point 12.

Rounded heads 19 of arms 5 engage arcuate surfaces 20 of their respective shoes 14, thereby supporting the turnover plate 4 and flask 3 in their inverted position.

Equalizing table C is mounted upon plunger 72 of cylinder 71 subject to lifting action of pressure of operating fluid through port 73 and connection 74 from valve D. The flask being in the elevated position, Fig. 1, the equalizing table C is lifted by the plunger to support it. The clamps connecting the plate 4 with the flasks being then removed, the flask may be lowered for the usual slight agitation and removal from the pattern, which depends from the turnover plate.

The parts being thus separated, arms 7 and the said plate may then be returned for an-

other operation, the flask being lowered by plunger 72 upon exhausting fluid pressure through valve D. The lowering of the plunger with cushioning action of the springs, etc., is generally the same as the operation described in the patent noted.

The construction of valve D is more fully described in my companion application Ser. No. 375,558.

What I claim is:—

1. In a flask turnover device, a flask support, elevating means therefor having an element engaging the flask support in one position and a bearing device for said element in another position.

2. In a flask turnover device, flask supports having sockets, a pair of turnover arms having interfitting engaging elements therefor, and controlling arms connected therewith having independent bearing members for said flask supports.

3. In a flask turnover device, flask supports having sockets, a pair of turnover arms having interfitting engaging elements therefor, controlling arms connected therewith having independent bearing members for said flask supports, and means for adjusting said bearing members.

4. In a flask turnover device, flask supports having tapered sockets, a pair of turnover arms having pivotally connected heads engaging said sockets, controlling arms pivotally connected with the heads, and means on the controlling arms for independently supporting the heads.

5. In a flask turnover device, flask supports having tapered sockets, a pair of turnover arms having pivotally connected heads engaging said sockets and provided with bearing terminals, controlling arms pivotally connected with the heads, and bearing blocks on the controlling arms adapted to engage and support the bearing terminals of the heads.

6. In a flask turnover device, flask supports having tapered sockets, a pair of turnover arms having pivotally connected heads engaging said sockets and provided with rounded bearing terminals, controlling arms pivotally connected with the heads and each having a bearing block adapted to engage one of said bearing terminals, and means for adjusting and tightening said bearing blocks.

In testimony whereof I hereunto affix my signature.

ROBERT F. RINGLE. 120
